COMBINED CRANK AND COUNTERWEIGHT

Kresten R. Jensen, Coffeyville, Kans.

Application December 30, 1937, Serial No. 182,598

4 Claims. (Cl. 74—591)

This invention relates to counterweights in connection with crank shafts.

An object of the invention is the provision of a counterweight adapted to be applied to a crank with means for adjustably locking the counterweight either in a balanced or unbalanced position or in any of the intermediate positions between the balanced and unbalanced positions.

Another object of the invention is the provision of a counterweight adapted to be applied to a crank with a particular means for securely fastening the counterweight in a plurality of positions with respect to the crank whereby the counterweight may be revolved through an arc of 180° and be retained in any degree desired throughout its 180° revolution.

A further object of the invention is the provision of a counterweight and a crank with a particular form of means for securing with facility the counterweight in any of a plurality of positions.

This invention will be best understood from a consideration of the following detailed description, in view of the accompanying drawing forming a part of the specification; nevertheless, it is to be understood that the invention is not confined to the disclosure, being susceptible of such changes and modifications as define no material departure from the salient features of the invention as expressed in the appended claims.

In the drawing:

Figure 1 is a side view in elevation of a counterweight and crank showing the counterweight in a balanced position,

Figure 2 is a vertical section taken along the line 2—2 of Figure 1,

Figure 3 is a view in elevation of a counterweight constructed in accordance with the principles of my invention shown in detached relation from a crank,

Figure 4 is a vertical section of the counterweight taken along the line 4—4 of Figure 3,

Figure 5 is a view in elevation of the crank per se showing a face which is opposite to that disclosed in Figure 1,

Figure 6 is a view in perspective of a wedge employed in clamping the counterweight to the crank, and

Figure 7 is a view in perspective of the wedge shown in Fig. 6 but showing the opposite face of the wedge.

Referring more particularly to the drawing, 10 designates generally a crank in the form of a plate in circular form having cut-out portions 11

at the upper end at each side of a vertical passing through the axis of the disc.

A pair of fingers 12 are formed by the cut-out portions 11 and by a vertical cut 13. These fingers have aligned horizontal passages 14 which are adapted to receive a bolt for drawing the fingers toward each other for clamping the disc 10 onto a drive shaft (not shown) when said drive shaft is received by an opening 15 formed at the inner end of the cut 13. A key-way 16 is formed in the disc 10 opens into the passage 15 and is adapted to receive a key carried by the shaft so that when the bolt has been secured in place the fingers 12 will be clamped onto the shaft and the key will lock the shaft to said disc.

A portion of the disc, as shown at 20, in Figs. 1 and 2 is enlarged so that in effect a ring is provided at the periphery of the disc having a greater thickness than the body portion 21 of the disc. 20

This face of the disc, as shown in Figs. 1 and 2, is provided with pockets 22 adapted to receive heads 23 of bolts 24 which extend through passages 25 in the ring portion 20 of the disc at spaced intervals of approximately 120° apart, 25 although a greater number of passages may be provided if desired. The opposite face of the disc is also provided with pockets 26 and these pockets are in alignment with the pockets 22. Each of the last-mentioned pockets is provided with an 30 inclined surface 27 for a purpose which will be presently explained.

Located centrally of the disc 10 and in a vertical line is an embossed portion 30 through which extends a pair of passages 31 and 32. These passages, as shown in Fig. 2, have tapered walls to receive the tapered end of a crank pin and the free end of the pin at this point is usually provided with a lock nut for securing the disc 10 to said pin. The passages 31 and 32 are upon opposite sides of the center of the disc so that when the disc is connected to the drive shaft at the passage 15 and revolved thereby, said disc will act as a crank.

A counterweight, generally designated by the numeral 35, has an eccentric opening 36 adapted to receive the periphery of the disc 10. An annular rib 37 is formed at the periphery of the opening 36 of the counterweight and has inclined walls 38 and 39 on its opposite faces. The 50 inclined walls 38 of the rib 37 are adapted to be engaged by pairs of lugs 40 and 41 which are located at opposite sides of the pockets 22 formed in one face of the disc.

A plurality of wedges 42 in the form of metal 55

blocks are adapted to be received by the pockets 26 and the other face of the disc and each wedge has an inclined shoulder 43 adapted to engage the inclined wall 27 of the pocket 26 formed in 5 the disc 10 and also the inclined face 39 of the counterweight 35. These wedges are provided with centrally disposed openings 45 through which the bolts 24 are adapted to pass so that when nuts 46 threaded onto said bolts are drawn 10 up tight the inclined shoulders 43 and 43a on the wedges 22 will securely clamp the counterweight 35 onto the disc 10.

It will be noted that the counterweight 35 is provided with a plurality of indicating marks 50 15 at spaced intervals and at the periphery of the opening 36 and these indications are numbered from zero to 10. It will be noted from Fig. 1 that the zero indication is in vertical alignment and at the top in Fig. 1 when the counterweight 20 35 is in the balanced position. The disc has co-operating graduations.

It will be noted from Figs. 2 and 7 that each of the wedges is provided with a pocket 55 to receive the nut 46 on a bolt 24 and this pocket 25 forms an enlarged open end for the opening 45 and is located at the outer face of each wedge.

When the crank disc 10 and the counterweight 35 are sold to a customer a pamphlet is attached thereto giving instructions to the purchaser how 30 the counterweight 35 may be positioned to obtain certain results and these instructions refer to the dial on the counterweight and their numbers adjacent the angularly disposed markings 50 adjacent the periphery of the opening 36 in said 35 counterweight. A purchaser then will be able to set the counterweight 35 in the proper position and secure said counterweight in place on the disc 10 by the tightening of the nuts 46 on the bolts 24. It will be seen by this construction that 40 a simple and efficient device is provided whereby the counterweight 35 may be positioned properly by loosening of the nuts 46 and then tightening said nuts after the counterweight has been set. The only requirement for setting the counterweight to give the best results will be the simple 45 loosening of the bolts.

By the use of the adjustable counterbalance illustrated and described herein the counterbalance may be moved from balanced to the extreme unbalanced position, thereby enabling the operator to obtain the balance on the crank at various loads during reciprocating motion in which the cranks may be used singly or in multiples.

55 I claim:

1. A crank comprising a disc having an eccentric passage to receive a drive shaft, a circular counterweight having an eccentric opening receiving the periphery of the disc and provided 60 with an annular rib at the periphery of the opening against which the periphery of the disc bears, said disc having spaced pockets at the periphery thereof and on opposite faces, wedges received in the pockets in one face and engaging 65 the rib, headed bolts passing through the pockets

and wedges, the heads of the bolts being seated in the pockets in the other face and nuts for drawing the bolts up tight to clamp the counterweight in an adjusted position on the disc.

2. A crank comprising a disc having an eccentric 5 passage to receive a drive shaft, a circular counterweight having an eccentric opening receiving the periphery of the disc and provided with an annular rib at the periphery of the opening against which the periphery of the disc bears, 10 said disc having spaced pockets at the periphery thereof and on opposite faces, wedges received in the pockets in one face and engaging the rib, headed bolts passing through the pockets and wedges, the heads of the bolts being seated in 15 the pockets in the other face and nuts for drawing the bolts up tight to clamp the counterweight in an adjusted position on the disc, the counterweight adjacent the periphery of the eccentric opening being provided with a graduated scale 20 which cooperates with a point on the disc to determine the proper annular position of the counterweight on the disc to obtain a predetermined counterbalancing of the shaft.

3. A combined crank and adjustable counterweight 25 comprising a counterweight having an eccentric opening, a disc received by said opening and having an eccentric opening to receive a drive shaft, said counterweight adapted to be revolved on the disc for adjustably positioning 30 the counterweight on said disc, lugs on the disc engaging the counterweight at one face thereof, means engageable with the opposite face of the disc and counterweight, means for clamping the last-mentioned means against the disc and counterweight for drawing the counterweight tight against said disc, the counterweight and said disc having cooperating graduations for indicating varying conditions of counterbalancing between a zero position and a point diametrically opposite 40 the zero position, said disc having a split portion adjacent the eccentric opening therein, the split portion normally aligning with the zero indication on the counterweight.

4. A crank in the form of a disc having a portion of the periphery cut away at opposite sides of a diameter to provide clamping fingers, said fingers having an opening located eccentrically of the disc to receive a drive shaft, said disc having eccentrically disposed passages to receive a crank 50 pin, a weighted ring having an eccentric opening, the periphery of said opening received by the periphery of the disc, said disc having the portion bordering the periphery raised above the main body portion of the disc, the raised portion having 55 pockets in the opposite faces thereof, bolts provided with heads seated in the pockets in one face, wedges located in the pockets in the other face and engaging one face of the ring, means on the other face of the ring engaging the first-mentioned face of the disc, and nuts in the wedges for drawing up the bolts for causing the ring to be 60 clamped to the disc.

KRESTEN R. JENSEN.
